TWO-SPEED, VARIABLE PRESSURE GARMENT PRESS

Edmund N. Neckel, North College Hill, Ohio, assignor, by mesne assignments, to McGraw-Edison Company, a corporation of Delaware

Filed Dec. 9, 1958, Ser. No. 779,114

8 Claims. (Cl. 38—41)

This invention relates to a novel and improved garment press of the so called "scissors" type wherein one of the pressing members is carried on a lever arm which is pivoted for swinging movement of its pressing member towards operative contact with a cooperating member.

My invention will be described in connection with a press having a fixed bed or buck, the press head being mounted on the end of a lever arm of the first class. Two sources of motive power are provided for operation of the head lever. One source consists of a motor for moving the head into operative contact with the buck. A second source comprises a booster ram, and motive power therefor, including an air-impelled piston and means for its operation, whereby intensified pressure may be applied to the work in the final increment of pressing movement of the head lever.

One object of the invention is to provide a press of the character defined in the last preceding paragraph which affords greater ease, convenience, and versatility of operation than could be achieved with previous presses of this general type.

A further object of the invention is to provide a press of the character above described in which the press closing means can be controlled to operate at one of two different speeds.

A further object of the invention is to provide a press of the character described in which means is provided for closing the press to relatively light pressing engagement and for applying additional heavier pressure at the will of the operator.

A further object of the invention is to provide a press of the character described in which means is provided for holding the pressing parts in pressing engagement during manual operation of the control element, or for maintaining the pressing parts in pressing engagement at a sustained predetermined pressure, independently of any manually maintained control element position.

Other objects and advantages will be apparent from a study of the following description of one embodiment of the invention in conjunction with the following drawings in which:

Fig. 1 is a side elevational view of a garment press embodying the invention, a side-frame portion being broken away to show certain operating parts.

Fig. 2 is a fragmentary front elevational view of the lower front portion of the press showing pedal operating elements.

Fig. 3 is a semi-diagrammatic view of certain air circuits, control valves and operating means therefor, and press head operating cylinders.

Fig. 4 is an enlarged fragmentary sectional view of a quick-release exhaust valve for the heavy pressure cylinder.

Figs. 5 and 6 are sectional views taken on the respective lines 5—5 and 6—6 of Fig. 4.

Referring first to the general structural features of the press shown in the drawings, there is provided a frame 10 on which a head lever 11 is pivotally mounted at 12. A

2

head 13 is supported at one end of the lever 10. The lever is of the first order, and is responsive to two power sources, whereof one source is adapted to supply press closing movement and the other source is adapted to exert a predetermined amount of pressure after the press has been closed, as will be described.

The curved end portion of lever 11 is pivotally connected at 14 to the piston rod 15a of a heavy pressure air cylinder 16. Cylinder 16 is pivotally mounted at 17 to a cross brace 18 on the frame. A press-closing air cylinder 19 is pivotally connected on the side frame at 19a, and has a piston rod 19b connected to the head lever at 20. A spring return means 21 is also connected to the head lever at 20, and is anchored at the other end to the cross brace 18.

This press operating arrangement provides an over-center arrangement for the pivot point 14 of the heavy pressure air cylinder 16. When the press is open, as shown in Fig. 1, the pivot point 14 lies to the right of the center line between points 12 and 17, and when the press head moves to closed position the pivot point 14 moves to the left and comes to rest at a location to the left of said center line. It will also be obvious that during such press closing swing the piston shown in broken line in cylinder 16 moves inwardly to reduce the cylinder head volumetric capacity during the swing of the pivot point 14 towards the center line, and then moves outwardly again to increase the cylinder head volumetric capacity during the swing of the pivot point 14 from the said center line to head-closed position.

Vacuum pipe 22 communicating with the interior of buck 23 has a valve 24 controlled by linkage 25 and foot pedal 26. The latter is pivoted on a shaft 27 (Figure 2), in the frame, and has a portion 26a at the other end arranged to operate exhaust valve 77 of the air control, later to be described. Also shown in Figure 2 is foot pedal 28, freely pivoted on shaft 27, and connected by linkage 29 (Figure 1) to the buck steam valve. Head steam control is provided, having a manual lever 30. Head and buck steam piping is indicated at 31.

With the press open, the control parts are in the condition shown in Figure 3 (the motors 16 and 19 are vertical in the diagram but would actually, of course, be at the angle shown in Figure 1). To close the press, the operator actuates either valve 32 or 33, the former being for standard, relatively high speed closing, and the latter for slow closing. The valves may be operated by any suitable push buttons, levers, etc. As here indicated, fairly wide manuals 34, 35, 39 are provided, spaced somewhat across the front edge of the press table 36. Slow speed manual 35 is freely journaled on a supporting shaft 37. Manual 34 is pinned to the shaft, as indicated at 38; and the shaft, extending to the other side of manual 35, also has pinned to it a manual 39, so that either manual 34 or 39 will operate normal speed valve 32.

Assume first that the press is to be closed at normal speed. Compressed air from source is in pipes 40, 41, and, at a predetermined pressure from regulator 42, in pipe 43 and the inlet chamber of valve 32. This is a conventional type of combination inlet-exhaust valve, the inlet valve 44 being normally closed by pressure of the air and by spring 45. Upon operation, now, the inlet valve opens and exhaust 46 seats. Air is thereby admitted through pipe 47 to inlet 48a of directional valve 48. This is a commercially available item, employing a rubber ball 48b which is moved by the incoming air into closing relation with the opposite inlet port. The air then goes to press-closing cylinder 19, a conventional single-acting motor, by way of pipe 49.

To close the press at slow speed, valve 33 is operated by means of manual 35. Air under line pressure in pipes 40, 50 and the inlet chamber of valve 33 is thereby

admitted through connecting pipe or nipple 51 to needle-check valve 52. Passage in this direction being prevented by ball valve member 52a, the air goes through needled orifice 52b, the rate of flow, but not the pressure, of course, being thereby suitably reduced. By way of nipple 53 the air goes to inlet 48c of directional valve, and then by pipe 49 to cylinder 19.

While in the present embodiment the air supply for normal closing comes through pressure regulator 42, whereas the air supply for slow closing is at line pressure, this is not particularly significant. Conventionally, a pressure regulator is provided in air presses to avoid too much variation in operation. Some variation in pressure in the "slow" circuit has a negligible effect on the closing, however, because of the throttling. Both circuits actually could have the same air supply.

The operator holds one or the other of the valves 32 or 33 operated the desired time, and releases the valve to open the press. Air exhausting from motor 19 goes back through pipe 49 to directional valve 48 and to the valve that has been used. From port 48c the air would pass unchecked through valve 52 and through valve 33, by way of exhaust port 33a, to a muffler 54. From the other port 48a of the directional valve the air would vent through pipe 47 to valve 32 and out the exhaust port 32a to the muffler. Mufflers may be used on all the exhaust ports, or may be dispensed with.

If, with the press closed under normal light pressure, additional pressure is deemed necessary, the operator actuates either valve 55 or 56 on the press head by depressing manual 57 or 58. As previously mentioned, this allows the pressure to be controlled in different ways. Assuming that only a short application of pressure is desired, the operator uses manual 57, opening valve 55 to apply pressure so long as the valve is held operated. Air from source, pipes 40, 59, 60, and the inlet chamber of valve 55 is admitted, on valve opening, to pipe 61 and thence to port 62a of directional valve 62 and out through pipe 63 to port 64a of quick exhaust valve 64 and therethrough to connecting nipple 65 and the inlet port of motor 16. The head being already closed at this time, the connecting point 14 of the head lever and the piston rod 15 is over-center to the rear, as indicated in broken lines, Figure 1, and the piston 15 is in extended position, although somewhat less than the press-open condition of Figure 3.

Refer at this point to the valve 64 (also Figs. 4-6). When the air enters through port 64a it acts against the bottom end of a piston valve assembly. The upper part is an exhaust valve 66 with a rubber or similar insert. The valve is slidable in a depending ring portion 64b of the valve cap which serves as a guide. A plurality of slots 64c in the guide ring 64b provide exhaust passageways when the valve is in lowered, open position. A stem 67 extending from the valve 66 has a reduced end part secured, as by pin 67a, to the portion 68 of the aforesaid piston valve assembly. The latter is slideable in cylindrical portion 64d of the valve body, and normally rests against a shoulder 64e. Freely fitting over stem 67 is a sleeve member 69 having a bottom flange 69a. An encircling spring 70 holds the sleeve down, with flange 69a seated on the portion 68 of the piston valve assembly, and covering a set of holes 68a therein. A shallow annular depression or groove 68b in the upper face of the piston connects the holes 68a. Spring 70 at its upper end bears against a washer member 71 slidably fitting on stem 67. The washer rests against the bottom of valve 66, and is also just touching the bottom edge of annular guide 64b.

The air entering below the piston valve assembly 68 first moves the assembly upward, thereby seating valve 66, closing the exhaust port 72. Note that the holes 68a are closed off by flange 69a at this time. As the valve engages the seat, piston 68 is stopped from further upward movement, but the air now lifts the flange slightly, against

spring pressure, and passes into the motor. When the flow of air into the motor ceases, the flange reseats, and the spring tends to push the piston-valve unit down. This is resisted, however, by the force in sealing direction exerted on the valve unit by the pressure differential—the exposed area above the valve being at atmospheric pressure. Thereafter, when pressure in the inlet pipe is released (when the operator releases valve 55), the exhaust valve quickly opens, due not only to the action of spring 70 but also because a differential pressure thereby occurs on piston 68, the higher pressure above the piston acting to push it down. The air under pressure in the motor thus exhausts by a short path through valve passages 64c, port 72 and muffler 73.

During the opening and the closing of the press, motor piston 15 makes a down and up reciprocation, so that a single snubbing means serves to check the head as it approaches the buck or the full-open position. In the present embodiment ball check 74 in the cylinder head allows free ingress of air, through pipe 75 and muffler 73, during the down stroke of the piston. As the piston begins the upstroke the check ball closes. The enlarged section 15b of the piston rod is, for a short period, out of the bore 16a, permitting free escape of the air through this bore, pipe 75 and muffler 73. Thereafter, section 15b enters this bore with some small amount of clearance, throttling this passageway to a large extent, and the escape of air is by this path plus the outlet 16b, adjustable by throttling screw 16c.

If, with the head closed under normal light pressure by use of valves 32 or 33, a sustained heavier pressure is desired, valve 56 will be actuated rather than valve 55. Air from pipes 40 and 59 and the inlet chamber of valve 56 is admitted to pipe 76, pedal-operated release valve 77, therethrough to port 62b of directional valve, and through pipe 63 to inlet of valve 64 at the high-pressure motor. A branch pipe 78 goes to a pressure gauge 79. The operator holds the valve 56 operated just long enough to attain the desired pressure, or this may also be done incrementally by quick opening and releasing of the valve, a certain period of time being required for the air to enter the motor and build up to full line pressure. At any intermediate point the valve 56 may be released to hold that particular pressure. This valve is arranged to trap the air beyond it, the valve being so adapted by plugging the exhaust port 56a and using an air-sealed valve stem 56b. To open quick-exhaust valve 64, pedal-operated release valve 77 is operated, releasing the air pressure in pipe 63. Port 62b of the directional valve has been opened the ball member 62c being held against opposite port 62a by the air pressure. It may be noted that whenever motor 16 is energized, the closing motor 19 may be de-energized, i.e., the operator may release the closing valve manual.

It will now be apparent that the garment press hereinabove described can be closed at either one of two speeds, namely the normal or relatively high speed and the lower speed. The latter speed is of considerable advantage when pressing work pieces of light weight, or which are otherwise susceptible to disarrangement by the sweep of escaping air if the press head approaches the buck at fairly rapid speed.

It will further be apparent that the press hereinabove described may be manually held, for a brief period, in pressing engagement with the work, or, at the operator's choice, the press head may be brought to engagement with the work at any selected pressure within the working pressure range of the press, and thereafter maintained under said selected pressure until disengaged when the operator chooses. A quick release exhaust valve is provided for this purpose.

What is claimed is:

1. A laundry press of the character described having a movable pressing member, and a fixed pressing member, and means for moving said movable pressing mem-

ber towards working contact with said fixed pressing member including a fluid pressure motor operatively effective on said movable pressing member, and means for transmitting fluid pressure to said motor comprising a first pipe route and a second pipe route, each said route having its respective flow control means whereby to admit fluid pressure in one or the other selected route, either said route being independently operable on said motor to close said press, and flow restricting means in one said route to provide an available differentiation in press operating speed.

2. A laundry press as defined in claim 1 having, in combination therewith, a second fluid pressure motor also operatively effective on said movable pressing member, and means for energizing said second fluid pressure motor after press closing movement whereby to apply additional working pressure on said movable pressing member.

3. A laundry press of the character described having a movable pressing member and a fixed pressing member, a lever carrying said movable pressing member on one end thereof, said lever being pivotally mounted on said frame whereby to permit said movable pressing member to be moved towards and away from said fixed pressing member by movement of said lever, a fluid pressure motor operatively effective on said lever to produce said movement, first fluid pressure transmission piping means in communication with said motor, second fluid pressure transmission piping means in communication with said motor, each said piping means having its respective flow control means whereby to provide respectively alternative fluid flow control paths, either said path being independently usable to close said press, and flow restricting means in one said path to provide a difference in the rates of flow available in said paths whereby to permit respective variations in press-closing speeds.

4. A laundry press as defined in claim 3 having, in combination therewith, a second fluid pressure motor also operatively effective on said lever, and means for energizing said second fluid pressure motor after press-closing movement whereby to apply increased working pressure on said movable pressing member.

5. A laundry press of the character described having a movable pressing member, and a fixed pressing member, means for moving said movable pressing member to working contact with said fixed pressing member, a fluid pressure motor operatively effective on said movable pressing member when it reaches working contact, means for transmitting fluid pressure to said motor through a pipe route having therein a control valve and a valve operating member, said valve being biased to pressure interrupting, exhaust position and being adapted to pass pressure fluid only while said valve operating member is actuated, and alternative means for transmitting pressure fluid to said motor including a second pipe route having therein a second control valve and a valve operating member, means for maintaining pressure in said second pipe route even after release of said second valve operating member, and means independent of said second control valve for exhausting pressure in said second pipe route after any determined interval.

6. A laundry press of the character described having a movable pressing member and a fixed pressing member, means for moving said movable pressing member towards working contact with said fixed pressing member including a fluid pressure motor operatively effective on said movable pressing member, means for transmitting fluid pressure to said motor comprising a first pipe route and a second pipe route each said route having its respective flow control means whereby to admit fluid pressure in one or the other selected route, either said route being independently operable on said fluid pressure motor, flow restricting means in one said route to provide an available differentiation in press operating speed, a second fluid pressure motor also operatively effective on said movable pressing member after it reaches

working contact, means for admitting fluid pressure to said second motor through a third pipe route having therein a control valve and a valve operating member, said valve being biased to pressure interrupting, exhaust position and being adapted to pass pressure fluid only

5 while its valve operating member is actuated, and alternative means for transmitting fluid pressure to said second motor including a fourth pipe route having therein a second control valve and a second valve operating member, means for maintaining pressure in said fourth pipe route even after release of said second valve operating member, and means independent of said second control valve for exhausting pressure in said fourth pipe route after any determined interval.

10 7. A laundry press of the character described having a movable pressing member, and a fixed pressing member, means for moving said movable pressing member to working contact with said fixed pressing member, a fluid pressure motor operatively effective on said movable pressing member when it reaches working contact, means for transmitting fluid pressure to said motor through a pipe route having therein a control valve and a valve operating member, said valve being biased to pressure interrupting, exhaust position and being adapted to pass pressure fluid only while said valve operating member is actuated, and alternative means for transmitting pressure fluid to said motor including a second pipe route having therein a second control valve and a valve operating member, means for maintaining pressure in said second pipe route even after release of said second valve operating member, and additional valve means in fluid flow communication with said second pipe route, and disposed adjacent to said motor, and normally biased to open, motor-exhaust position, but being movable to closed position by incoming pressure fluid.

15 8. A laundry press of the character described having a movable pressing member and a fixed pressing member, means for moving said movable pressing member towards working contact with said fixed pressing member including a fluid pressure motor operatively effective on said movable pressing member, means for transmitting fluid pressure to said motor comprising a first pipe route and a second pipe route each said route having its respective flow control means whereby to admit fluid pressure in one or the other selected route, flow restricting means in one said route to provide an available differentiation in press operating speed, a second fluid pressure motor also operatively effective on said movable pressing member after it reaches working contact, means for admitting fluid pressure to said second motor through a third pipe route having therein a control valve and a valve operating member, said valve being biased to pressure interrupting, exhaust position and being adapted to pass pressure fluid only while its valve operating member is actuated, and alternative means for transmitting fluid pressure to said second motor including a fourth pipe route having therein a second control valve and a second valve operating member, means for maintaining pressure in said fourth pipe route even after release of said second valve operating member, and additional valve means in fluid flow communication with said fourth pipe route, and disposed adjacent to said second fluid pressure motor, and normally biased to open, motor-exhaust position, but being movable to closed position by incoming pressure fluid in said fourth pipe route.
